UNITED STATES PATENT OFFICE.

JOHN H. SCHULZE, SR., OF HEMPSTEAD, NEW YORK.

REINFORCED CONCRETE CONSTRUCTION.

Application filed April 14, 1921. Serial No. 461,300.

To all whom it may concern:

Be it known that JOHN H. SCHULZE, Sr., a citizen of the United States of America, residing at Hempstead, in the county of 5 Nassau and State of New York, has invented new and useful Improvements in Reinforced Concrete Constructions, of which the following is a specification.

The object of the invention is to provide 10 a reenforced concrete construction and more especially a horizontal slab construction adapted for floor and ceiling spans of expanded areas, to be used under conditions necessitating the employment of the minimum number of uprights at relatively long 15 intervals, or where the character of the building is such as to make the use of comparatively long spans preferably as a means of avoiding the obstruction of the space in 20 the room or area beneath the floor and ceiling structure, and in that connection to provide an arrangement of reinforcing means whereby sagging between the supports, due either to the weight of the structure or 25 superimposed objects, is prevented while affording efficient means for applying and holding a plaster coating to form a finishing surface for the ceiling; and with this object in view the invention consists in a construction and combination of parts of which a 30 preferred embodiment is shown in the accompanying drawings, wherein:—

Figure 1 is a plan view showing one complete span and adjacent portions of adjoining spans of a roof and ceiling construction embodying the invention.

Figure 2 is a sectional view taken on the plane indicated by the line 2—2 of Figure 1.

Figure 3 is a sectional view on an enlarged 40 scale taken on the plane indicated by the line 3—3 of Figure 1.

Figure 4 is a detail view showing reinforcement for the lintels of openings suitable for windows and doors.

Figure 5 is a vertical sectional view of a 45 window or door lintel.

Figure 6 is a vertical sectional view on the plane indicated by the line 6—6 of Figure 1 to show the means whereby the extremities 50 of the crossed tensile bars are anchored.

Figure 7 is a detail view of one of the anchoring plates.

Figure 8 is a view of one of the terra cotta blocks prior to the division thereof to form 55 the plastering anchors.

Figure 9 is a plan view of a series of the

plastering anchors to show the preferred relative arrangement of the ribs thereof.

The structure embodies essentially the crossed or intersecting tensile rods 10 provided with turn buckles 11 or like means for varying the tension thereof and having their outer or remote extremities engaged with suitable hooks 12 on anchor plates 13 which are engaged with anchor pins 14 disposed vertically in the walls shown at 15 or at the intersection of said walls and girders 16, or at the intersection of two angularly extending girders as indicated at 17, said anchor pins being held in place by the anchor frames 18 embedded in said walls or girders.

The plaster anchoring elements 19 are formed as blocks indicated in detail in Figure 8 with exterior key grooves 20 and inwardly directed ribs 21 kerfed or weakened at 22 to facilitate separation or breakage preparatory to setting in the wall, and in positioning the same they are disposed upon a false frame or form (not shown) as in the ordinary practice with their flanges upwardly or inwardly directed as indicated in Figures 2 and 3, beneath the plane of the tensile bars 10 and adapted to support a metallic reinforcing frame or netting 23 to receive the concrete or cement filler 24 in which, as in the ordinary practice, the battens 25 may be embedded for the attachment of the flooring boards 26.

Supplemental to the intersecting diagonally disposed tensile bars 10 are auxiliary tensile rods 27 engaged at their outer ends to anchor rods 28 embedded in the walls or girders and engaged at their inner ends with bridge rods 29 supported by the tensile bars 10 and spanning the angles at the intersecting portions thereof.

At the openings designed for windows and doors, and more especially those openings which are formed in the exterior walls are arranged the saddle beams 30 with which are connected reinforcing elements 31 engaging longitudinal reinforcing rods 32 embedded in the concrete filler as indicated at 33 between the exterior facing masonry 34 of bricks or like material and the inner layer of plaster anchoring elements 19 corresponding with those employed in connection with the floor and ceiling structure.

The ribs of these plaster anchoring elements are preferably disposed in intersecting relations as indicated in Figure 9 so as to form effective keys by the concrete or ce-

ment which is employed as a filler and which occupies the spaces between said ribs.

The girder construction as indicated in Figure 3 includes the metallic bars 35 which 5 may be of any approved construction embedded in the concrete filler 36 and covered exteriorly by the plaster anchoring elements 19 of which those on the under side of the girder are disposed with their ribs in trans- 10 verse relation thereto.

The invention having been described, what is claimed as new and useful is:—

1. A reenforced concrete span having intersecting diagonally disposed tensile bars 15 terminally anchored in wall or girder structures, and means for adjusting the tension of said bars, the anchoring means consisting of vertical anchor pins and anchor plates engaged with said pins and provided with 20 hooks for engagement by eyes at the extremities of said tensile bars.

2. A reenforced concrete span having intersecting diagonally disposed tensile bars 25 terminally anchored in wall or girder structures, and means for adjusting the tension of said bars, supplemented by auxiliary tensile rods radiating from the point of intersec-

tion of said tensile bars, connected at their outer ends to anchor bars in the wall and girder structures and engaged at their inner ends with bridge pieces spanning the angles between said tensile bars. 30

3. A reenforced concrete span having intersecting diagonally disposed tensile bars terminally anchored in wall or concrete 35 structures, auxiliary tensile rods disposed in bisecting relation with the angles formed by said intersecting diagonally disposed bars and connected at their outer ends to anchor bars in the wall and concrete structures and 40 operatively connected at their inner ends with the diagonally disposed bars.

4. A reenforced concrete span having intersecting diagonally disposed tensile bars, 45 said bars being longitudinally extensible and contractible, anchor pins fitted in wall or girder structures, and plates engaging with said pins and provided with hooks for engagement by eyes to the extremities of said tensile bars.

In testimony whereof he affixes his signature.

JOHN H. SCHULZE, Sr.
